UNITED STATES PATENT OFFICE.

WILLIAM A. IVES, OF NEW HAVEN, CONNECTICUT.

BIT-STOCK.

SPECIFICATION forming part of Letters Patent No. 248,470, dated October 18, 1881.

Application filed April 16, 1881. (No model.)

To all whom it may concern:

Be it known that I, WM. A. IVES, of New Haven, in the county of New Haven and State of Connecticut, have invented a new Improvement in Bit-Braces; and I do hereby declare the following, when taken in connection with the accompanying drawings and the letters of reference marked thereon, to be a full, clear, and exact description of the same, and which 10 said drawings constitute part of this specification, and represent, in—

Figure 1, a side view; Fig. 2, sectional side view; Fig. 3, vertical central section through both jaws; Fig. 4, section on same line as Fig. 15 3, showing the jaws as holding the bit; Fig. 5, vertical section of the socket at right angles to the section Fig. 3; Fig. 6, section on line *xx* of Fig. 5.

This invention relates to an improvement in 20 that class of bit-braces in which is a stationary seat for the tip of the bit-tang, and a pair of jaws arranged to grasp upon the shank of the bit, over the shoulder of the tang, to draw and hold it onto its seat, the object of this invention being to retain the jaws in a firm open 25 position when not in use, and also to insure their moving together to properly grip and hold the bit; and it consists in a socket threaded upon its exterior surface with radially-opposite 30 slots, within which the gripping-jaws are arranged, a stationary seat in the socket for the tip of the tang, the said two jaws hung to a slide in the socket below the seat, said slide resting upon a spring to force it outward, the 35 said seat serving to open and hold the jaws open as they are forced outward by the spring, combined with an internally-threaded sleeve working upon the outside of the socket to force the jaws inward toward the tang-seat, and also 40 toward each other, all as more fully hereinafter described.

A represents the arm of the bit-brace, to which the socket B is attached. This socket B is screw-threaded upon its outside, as seen 45 in Fig. 2, and has a longitudinal slot, *a*, diametrically through it, in the usual manner for this class of braces.

C is the sleeve, internally threaded to work 50 upon the outside of the socket, to operate upon the inclined backs of the jaws D in substantially the usual manner.

Centrally within the socket a bridge, *d*, extends from side to side, as seen in Figs. 3, 5, and 6. In this bridge *d* a cavity, *e*, is made as a seat for the lower end of the bit-tang E, 55 as seen in Fig. 4 and in broken lines, Fig. 3. Below the bridge *d*, and through the slot in the socket, a slide, F, is arranged, seated upon a spring, G, the tendency of which is to force the said slide upward. This slide has a recess 60 in its upper side, into which the lower end of the jaws D set, and through the slide and lower end of the jaws a pin, *b*, is placed, which serves to secure the jaws to the slide. The hole through the jaws for the pin is slightly 65 larger than the pin, so as to allow the requisite play of the jaws. At the outer end the inner faces of the jaws are provided with internal projections or shoulders, *f*, to grasp over the shoulder of the tang, as seen in Fig. 4. At the 70 lower end of the jaws and above their connection with the slide F the inside of each jaw is inclined, as at *n*, upward and outward, and so that when the jaws are in their extreme outward position, forced there by the spring G, 75 the inclined surfaces *n* strike upon the under side of the bridge *d* and force the jaws not only to their outer position, but to their extreme open position, as seen in Fig. 3. Held in this position against the bridge the outer 80 end of the jaws are held back against the mouth of the sleeve, so that they remain in that position to receive the bit-tang, and do not have that freedom which permits them to tip inward, as in many bit-braces, and which freedom causes a difficulty or inconvenience in inserting the bit.

The operation of this brace is as follows: The jaws being open, as in Fig. 3, the tang of the bit is introduced between the jaws, its tip 90 set onto the seat or cavity *e*. The distance between the bridge and the end of the jaws in this position should be greater than the length of the tang. When the bit has been thus inserted the sleeve is rotated to draw it onto the 95 socket, and in so doing it bears upon the outer end of the jaws, moving them inward against the shank of the bit, and so soon as they come to a bearing on the shank of the bit they then are forced inward toward the seat, compressing the spring G until they engage the shoulder of the tang, as seen in Fig. 4. To release 100

the bit, reverse the operation, in doing which the jaws are forced outward and open by the spring G acting upon the slide F, as before described.

By this construction the jaws are positively brought together and cannot be disarranged, and are always in the condition and position to readily receive and grasp the bit.

From the foregoing it will be understood that I do not broadly claim a bit-brace having gripping-jaws arranged to move both longitudinally and toward each other; neither do I broadly claim, in combination with such jaws, a stationary seat in the socket for the end of the tang, as such, I am aware, is not new; but

What I do claim is—

1. In a bit-brace, the combination of the screw-threaded socket B, longitudinally slotted and constructed with the bridge d, to form a seat for the tip of the tang, the slide F, arranged to move longitudinally in the slot of the socket and below the bridge, the spring arranged to force the said slide toward the bridge, the jaws D D, hung upon a pivot in the said slide, and

the internally-threaded sleeve arranged to be moved longitudinally on the socket and to force the said jaws longitudinally inward and toward each other, substantially as described.

2. In a bit-brace, the combination of the screw-threaded socket B, longitudinally slotted and constructed with the bridge d, to form a seat for the tip of the tang, the slide F, arranged to move longitudinally in the slot of the socket and below the bridge, the spring arranged to force the said slide toward the bridge, the jaws D D, hung upon a pivot in the said slide, constructed with the inclines n upon their inner face, said inclines arranged to work against corresponding points on the said bridge to open the jaws, and the internally-threaded sleeve arranged to be moved longitudinally on the socket and to force the said jaws longitudinally inward and toward each other, substantially as described.

WM. A. IVES.
